FIG. 2.

INVENTOR

WITNESS:

Robt P. Kitchel.

John S. Haug
BY
Augustus B. Streightoff,
ATTORNEY.

UNITED STATES PATENT OFFICE

JOHN S. HAUG, OF PHILADELPHIA, PENNSYLVANIA, ASSIGNOR TO THE U. G. I. CONTRACTING COMPANY, OF PHILADELPHIA, PENNSYLVANIA, A CORPORATION OF DELAWARE

GAS PRODUCER

Application filed May 21, 1928. Serial No. 279,569.

The present invention relates to gas generators in which there are provisions to secure a distribution of the fuel fed to the top of the fuel bed in such a manner as to deposit the finer fuel at the periphery and the coarser fuel in the center and which generator is equipped with a grate having means for the distribution of air and steam and also means for continuous ash removal.

10 One object of the present invention is to provide means for the distribution of air and steam along with means for continuous ash removal which are better adapted to the method of fuel distribution above referred 15 to than are present in any producer or generator or, more accurately, in any producer or generator grate of which I am aware.

The position and shape of the combustion zone at any point in the fuel bed of a gas producer or generator depends on the ratio of 20 the rate of combustion to the rate of ash removal at that point. If the combustion rate is uniform and if the ash is removed uniformly 25 as fast as formed in all parts of the fuel bed, the combustion zone will be stationary. If in any part of the fire, the combustion 30 proceeds at a higher rate than the corresponding ash removal, the combustion zone rises at that point tending to produce blow 35 holes.

A gas generator or gas producer of the type recited is able to gasify a low grade of fuel containing a high percentage of fines due to the distribution of the fines to the 40 periphery of the fuel bed and the coarser fuel to the center, thereby counteracting the inherent tendency to produce a high combustion rate at the periphery or sides and a low rate in the center. However, undue activity 45 of combustion is promoted in the center of the fuel bed, with grates known to me.

In the present invention air is admitted to 50 an annular ring of fuel at the bottom of the bed, and this annular ring extends inward from points relatively close to the periphery. A substantial section or part of the fuel bed in the center has no air admitted to it directly, but due to the porosity of the fuel in the center a sufficient amount of air traverses the 55 center of the fuel bed to secure the desired

rate of combustion there, and in the present invention there is provided improved ash extraction means in the central section where the air is not admitted directly, and this increased extraction at the center assists in lowering the combustion zone in the center with the avoidance of blow holes, and it also gives a more effective fire depth and secures more efficient gasification of the fuel, all in respect to gas generators and grates therefor with 60 which I am familiar.

In the present invention the central area of the grate is flattened causing a better distribution of the blast by opposing the formation of a porous path at the juncture of the ash line with the grate which path if formed would allow almost as much air to 65 find its way to the center of the fire as would be the case if air blast were introduced at the center of the grate, and the flattened portion of the grate is provided with ash extraction means.

The invention also comprises the improvements to be presently described and finally claimed and in the following description reference will be made to the accompanying drawings forming part hereof and in which

Figure 1 is a diagrammatic view, principally in central and vertical section, of a gas producer or producer embodying features of the invention, and

Fig. 2 is a similar view with parts omitted and illustrating a modification.

Referring more particularly to Fig. 1 the gas producer shell 1 is shown as provided with a refractory lining 2. A rim feed charging mechanism happens to be selected from other mechanisms adapted to produce the described distribution of finer particles at the periphery of the fuel bed as indicated at *a* and coarser particles at the center as indicated at *b*. The rim feed mechanism is shown at 3 and it includes a charging hopper 4 about the periphery of the producer top and feeding fuel to the entire periphery of the fuel bed. The opening, through which the rim feed mechanism 3 and charge hopper 4 feed, is normally closed at the upper end of the hopper (not shown). The top

of the fuel bed is indicated at *c*. The producer is provided at its top with a gas offtake conduit 66 and may be provided adjacent its top with a depending flange or wall 77. The lower part of the gas producer is provided with a water jacket 5 having a bare metallic inner wall 55. As far as has been described there is nothing new in and of itself. The eccentric grate is generally indicated at 6 and it is of the mechanical variety. As shown the grate consists of a cylinder 7 surmounted by a truncated stepped cone which is provided with ports 8 arranged to form an inlet portion generally annular in outline. There is nothing novel in and of itself about the grate so far as described.

Above the truncated cone there is provided a flattened top 9 which is equipped with curved cutting blades 10. The flattened top is imperforate, or otherwise stated, has no ports.

The grate is rotated by the worm and worm wheel mechanism 11. 12 is the ash pan and 13 is a plow. 14 indicates means for sealing the grate such as a water seal.

Air or mixed air and steam admitted to the interior of the grate through the conduit 15 flows into the fuel bed through the ports 8 and is delivered directly to an annular ring of the fuel bed extending from the periphery inward and comprising the finer particles. No gas making fluid, air or mixed air and steam, passes through the top of the grate but due to the greater porosity of the fuel bed in the center sufficient air finds its way up through that section, as indicated by the arrows, thus the height of the combustion zone and also of the reduction zone in the center of the fuel bed is maintained comparatively near the grate or at a low level. This is further aided by the blades 10 which increase the rate of ash removal from the center of the fire and help to equalize the rate of combustion and the rate of ash extraction in the center part of the fuel bed.

The result of the coaction of feeding relatively coarse fuel such as bituminous coal in the center and fine fuel such as bituminous coal to the rim and of the annular admission of gas making fluid with the flattened imperforate top of the grate and the means thereon for ash extraction in the center of the fire, is illustrated by the position and shape of the combustion and reduction zones in Fig. 1. These zones extend uniformly across the entire fuel bed and the combustion zone in the center is quite close to the grate, giving an effective fuel bed depth and avoiding the formation of blow holes. The activity at the outer annulus of the fuel bed is insured and there is a consequent reduction in the quantity of unburnt fuel escaping from this portion.

At the rim part of the bottom of the fuel bed, ash passes through the space 17 pro-

vided between the part 7 of the grate and the sealing member 14.

The construction and mode of operation of the modification shown in Fig. 2 are as above described except that the grate 18 is of a cylindrical form and it is surmounted by a low cone, constituting the imperforate top, and carrying the cutting blades. The ports are indicated at 16 and are located in the cylindrical portion of the grate forming an inlet portion therein which is annular in its general outline.

It will be obvious to those skilled in the art to which the invention relates that modifications may be made in details of construction and arrangement and matters of mere form without departing from the spirit of the invention which is not limited to such matters or otherwise than the prior art and the appended claims may require.

I claim:

1. In a gas producer having a stationary cylindrical lower portion including a water jacket having a bare inner metallic wall; a grate structure having a cylindrical portion spaced from the wall of said producer to leave an annular space therebetween forming an ash outlet, said grate structure, including a conical portion supported by the lower cylindrical portion, said conical portion having ports for gas making fluids opposite the water jacket, and a flattened solid top portion having curved cutting ribs thereon, and means for introducing gas making fluids beneath the grate structure and to the ports.

2. In a gas producer having a fuel bed therein and having a stationary cylindrical lower portion including a water jacket in contact with the fuel bed; an eccentric grate structure having a lower portion spaced from the wall of said producer to leave an annular space therebetween forming an ash outlet, an annular inlet portion in said grate structure having ports therein through which gas making fluids pass, a solid top portion supported by said lower portion and by said inlet portion, upstanding cutting ribs on said top portion, and means for introducing gas making fluids beneath the grate structure and to said ports.

JOHN S. HAUG.
